FLUID TRANSLATING APPARATUS

Emil Ehret, Forest Hills, Pa., assignor to Westinghouse Electric & Manufacturing Company, East Pittsburgh, Pa., a corporation of Pennsylvania

Application August 23, 1934, Serial No. 741,125

6 Claims. (CL 230—184)

My invention relates to fluid translating apparatus, more particularly to a multi-cylinder reciprocating compressor, and it has for an object to provide improved apparatus.

5 A further object is to provide a construction of fluid translating apparatus wherein the cylinder head may be removed in a relatively simple manner without disconnecting pipes connected to inlet and outlet chambers in the cylinder head.

10 A further object is to provide fluid translating apparatus wherein auxiliary apparatus, such as oil separator and muffler, are incorporated in a simple manner.

In accordance with my invention, I provide 15 a crank case member having inlet and outlet headers; cylinder members in which the cylinders are formed and having inlet and outlet passages communicating with said headers; and cylinder heads having inlet and outlet chambers 20 providing communication between the cylinders and the inlet and outlet passages.

The above and other objects are effected by my invention as will be apparent from the following description and claims taken in connection with the accompanying drawings forming a part of this application, in which:

Fig. 1 is a side view, partly in section and partly in elevation, of a reciprocating compressor embodying my invention;

30 Fig. 2 is a plan view of the compressor, with certain parts removed, as seen on the line II—II of Fig. 1;

Fig. 3 is a vertical cross-section taken on the line III—III of Figs. 1 and 2;

35 Fig. 4 is a horizontal section taken on the line IV—IV of Fig. 3, showing the oil separator in the inlet header; and

Fig. 5 is a horizontal section taken on the line V—V of Fig. 3, showing the muffler in the 40 discharge header.

Referring to the drawings in detail, I show a reciprocating compressor 10 comprising a plurality of cylinders disposed in a row and driven by a motor 11 of any suitable type. The compressor includes a crank case 12, the major portion of which, in the present embodiment is a single casting. This casting has top, side, and bottom wall portions which are integral with each other, the side and bottom wall portions closing substantially the entire sides and bottom of the crank case. A crank shaft 13 is mounted in the crankcase, being journalled in bearings formed in discs 14 detachably secured in the crankcase. An opening 15 is formed in 55 the crankcase at the end remote from the motor

11, through which the crank shaft 13 and the discs 14 are removable as an assembly. The opening 15 is closed by a cover plate 16, which carries a lubricant pump 17 driven by the crank shaft 13 through a key and slot connection 18. The cover plate 16 also carries an oil filter 20 projecting, through an opening 19 into the lower portion of the crankcase, which forms a lubricant reservoir.

According to the present invention, the cylinders are formed by separate cylinder members 21, each of which, in the present embodiment, forms two cylinders 22. Each cylinder member is secured to the crankcase on a horizontal plane of division designated 23, and has a flange 24 seating on the flat finished surface provided on the crankcase along said plane 23, being secured thereto by tap bolts 25. The crankcase is formed with a circular opening 26 for each cylinder member, through which the connecting rods 27 are extended. The latter connect pistons 28 in the cylinders 22 to the crank shaft 13, being secured by bolts and nuts 28' to crank pins 29 between discs 30 of the crank shaft, which latter are concentric with the axis of the crank shaft.

Each cylinder member 21 is provided with a cylinder head 31, having an inlet or suction chamber 32 and a discharge chamber 33 divided by a partition 34, both chambers being common to the two cylinders 22. A valve assembly 35 is interposed between the cylinder member and the cylinder head, and includes a suction valve 36 for each cylinder providing communication between the suction chamber 32 and the cylinder, and a discharge valve 37 for each cylinder which permits flow of compressed refrigerant from the cylinder into the discharge chamber 33. The cylinder head 31 is secured to the cylinder member 21 by means of bolts 38, the valve assembly 35 being clamped between the cylinder head and the cylinder member.

According to the present invention, the crankcase is formed with an integral inlet or suction header 39 extending along one side of the row 45 of cylinders. As shown in Figs. 3 and 4, an oil separator 41 is disposed within the header 39. The gaseous fluid to be compressed, which is conveyed through a suction conduit 39a and a shut-off valve 39b, enters the header through an inlet opening 42 and passes through the oil separator 41. The oil separated from the vapor flows downwardly by gravity through a passage 43 in the crankcase to the lubricant reservoir in the bottom thereof. The header 39 is formed 55

with a connecting passage 44, for each cylinder member, extending upwardly and terminating in the plane of division 23. The oil separator 41 is inserted through the end of the header 39 adjacent the motor 16, which end is closed by a cover plate 40.

A discharge header 45 is also formed integrally with the crankcase on the opposite side of the row of cylinders. It is formed with connecting 10 passages 46 extending to the plane of division 23, one passage 46 being provided for each cylinder member, and with an outlet opening 47. A muffler 48 is provided within the discharge header 45. This muffler comprises a foraminated 15 tubular sheet metal member, rectangular in cross section, as shown in Fig. 3. Strips of screen 51 are wound around the tubular member 49 in the spaces between adjacent passages 46. At the 20 passages 46, the adjacent strips of screen 51 are spaced to provide a passage for the gaseous fluid. Stacks of vertically disposed screens 52 and 53 are wedged in the discharge header 45 on opposite sides of the strips of screen 51, the screens 52 having recesses 54 adjacent the 25 sages 46, to provide additional passageway for the gaseous fluid to enter the interior of the tubular member 49. The compressed fluid enters 30 through the several passages 46, between adjacent screens 51 into the interior of the tubular member 49, then outwardly through the outlet to 35 47, a shut-off valve 45a, and a conduit 45b to the condenser (not shown). The header 45 has an open end adjacent the motor 16, through which the muffler 48 may be inserted, and which is closed by an end plate 50.

Each cylinder member 21 is formed with an inlet passage 55 which is common to the two cylinders 22. The lower end of the passage 55 terminates in the plane of division 23 and communicates with the passage 44 of the inlet header 39. The upper end of the passage 55 terminates 40 in a plane 56, which defines the upper surface of the cylinder member 21 and against which the valve assembly 35 bears. The valve assembly 35 is provided with an opening 57 registering 45 with the passage 55 and providing communication between the passage 55 and the inlet chamber 32 in the cylinder head.

The cylinder member 21 is further formed with 50 an outlet or discharge passage 58, also common to the two cylinders 22 and disposed on the opposite side of the cylinder member. The lower end of the passage 58 terminates in the plane of division 23, in registry with the passage 46. The upper end of the passage 58 terminates in the 55 plane 56, and the valve assembly 35 is formed with an opening 59 providing communication between the discharge chamber 33 and the passage 58.

60 In operation, gaseous fluid to be compressed, from the conduit 39a and valve 38b, enters the inlet manifold through the inlet opening 42. Any oil entrained in the gaseous fluid, which is a condition encountered particularly in the case 65 of refrigerating compressors, is separated by the oil separator 41 and flows by gravity through the passage 43 to the bottom of the crankcase. The gaseous fluid flows upwardly through the several 70 passages 44, the passages 55, the openings 57, the inlet chambers 32 and the inlet valves 36 into the cylinders 22. Upon upward movement of the pistons 28, the gas is compressed and discharged through the discharge valves 37, the discharge chambers 33, the openings 59, the 75 passages 58 and 46, through the tubular member

49 of the muffler 48, and outwardly through the opening 47 of the discharge header, to the valve 45a and conduit 45b.

In disassembling the cylinder head, it is only necessary to remove the bolts 38, whereupon the cylinder head, and also the valve assembly 35, may be removed without disconnecting any pipes extending to the cylinder head or any other fluid inlet or outlet connections, which would otherwise be necessary, as in the prior constructions. 10 This is possible because the gaseous fluid is admitted and discharged through the plane of division between the valve assembly and the cylinders. Furthermore, the cylinder members may be likewise removed from the crankcase, by removing the tap bolts 28, without disengaging additional inlet or outlet connections. The connecting rods 27 may then be disconnected from the crank shaft by inserting a wrench through the opening 26 in the crankcase to remove the 20 nuts 28. The cover plate 16 is removed, and the crank shaft 13, with the bearing discs 14 thereon, may then be withdrawn through the opening 15, after which the bearing discs may be detached from the crank shaft. 25

From the above description, it will be seen that I have provided a compressor construction, for a plurality of cylinders, which may be dismantled without removing the crankcase or disturbing any pipe connections. The compressor 30 may be isolated from the remainder of the refrigerant circuit by closing the shut-off valves 38b and 45a.

A further advantage of the present construction is that a single inlet and outlet for the 35 entire group of cylinders is provided. The utilization of inlet and discharge headers for the oil separator and muffler eliminates the necessity for additional space which would otherwise be required and provides a more compact piece of 40 apparatus.

The construction of the crankcase provides a maximum of unbroken or integral wall area and reduces to a minimum the number and length of joints, thereby reducing the possibility of 45 leakage.

While I have shown my invention in but one form, it will be obvious to those skilled in the art that it is not so limited, but is susceptible of various changes and modifications without departing from the spirit thereof, and I desire, therefore, that only such limitations shall be placed thereupon as are imposed by the prior art or as are set forth in the appended claims. 55

What I claim is:

1. In a fluid translating machine, the combination of a crankcase member, a plurality of cylinder members secured to said crankcase member and arranged in a row and each having a cylinder formed therein, said crank case member having an inlet header on one side of said row and an outlet header on the other side thereof, both headers being formed integrally with the crankcase member, each of said cylinder members having inlet and outlet passages formed integrally therewith and communicating with said inlet and outlet headers, respectively, a cylinder head for each cylinder member having inlet and outlet chambers providing communication between said cylinder and said inlet and outlet passages, respectively, and valve means for controlling the flow of fluid between each cylinder and the associated inlet and outlet passages. 65

2. In a compressor, the combination of cylinder means having formed therein a plurality of 70

airs of cylinders, said cylinders being arranged in a row; said cylinder means having formed therein an inlet passage adjacent and common to each pair of cylinders and terminating in alignment with the ends of the cylinders and an outlet passage adjacent and common to the pair of cylinders and terminating in alignment with the ends of the cylinders; a separate cylinder head for each pair of cylinders, each head having an inlet chamber communicating with both cylinders and said common inlet passage, and an outlet chamber communicating with both cylinders and said common outlet passage and having a partition between the inlet and outlet chambers extending across each cylinder; valve means clamped between each cylinder head and the associated cylinders and including an inlet valve controlling communication between the inlet chamber and each cylinder and an outlet valve controlling communication between the inlet chamber and each cylinder and an outlet valve controlling flow between each cylinder and said outlet chamber; means clamped between each cylinder head and the cylinder means providing communication between the inlet chamber and the common inlet passage and communication between the outlet chamber and the common outlet passage; and means providing communication between the several inlet passages and a common inlet therefor.

3. In a compressor, the combination of cylinder means having formed therein a plurality of pairs of cylinders, said cylinders being arranged in a row; said cylinder means having formed therein an inlet passage adjacent and common to each pair of cylinders and terminating in alignment with the ends of the cylinders and an outlet passage adjacent and common to the pair of cylinders and terminating in alignment with the ends of the cylinder; a separate cylinder head for each pair of cylinders, each head having an inlet chamber communicating with both cylinders and said common inlet passage, and an outlet chamber communicating with both cylinders and said common outlet passage and having a partition between the inlet and outlet chambers extending across each cylinder; valve means clamped between each cylinder head and the associated cylinders and including an inlet valve controlling communication between the inlet chamber and each cylinder and an outlet valve controlling flow between each cylinder and said outlet chamber; and means clamped between each cylinder head and the cylinder means providing communication between the inlet chamber and the common inlet passage and communication between the outlet chamber and the common outlet passage.

4. In a compressor, the combination of cylinder means having formed therein a plurality of pairs of cylinders, said cylinders being arranged in a row; said cylinder means having formed therein an outlet passage adjacent and common to each pair of cylinders and terminating in alignment with the ends of the cylinders; a separate cylinder head for each pair of cylinders,

each head having an inlet chamber communicating with both cylinders and an outlet chamber communicating with both cylinders and said common outlet passage and having a partition between the inlet and outlet chambers extending across each cylinder; valve means clamped between each cylinder head and the associated cylinders and including an inlet valve controlling communication between the inlet chamber and each cylinder and an outlet valve controlling flow between each cylinder and said outlet chamber; means clamped between each cylinder head and the cylinder means providing communication between the outlet chamber and the common outlet passage; and means providing communication between the several outlet passages and a common outlet therefor.

5. In a compressor, the combination of cylinder means having formed therein a plurality of pairs of cylinders, said cylinders being arranged in a row; said cylinder means having formed therein an outlet passage adjacent and common to each pair of cylinders and terminating in alignment with the ends of the cylinders and also having inlet passages formed therein; a separate cylinder head for each pair of cylinders, each head having an outlet chamber communicating with both cylinders and said common outlet passage; valve means clamped between each cylinder head and the associated cylinders and including an outlet valve controlling flow between each cylinder and said outlet chamber; valve means controlling flow between each cylinder and an inlet passage; means clamped between each cylinder head and the cylinder means providing communication between the outlet chamber and the common outlet passage; and means providing communication between the several outlet passages and a common outlet therefor.

6. In a compressor, the combination of cylinder means having formed therein a plurality of pairs of cylinders, said cylinders being arranged in a row; said cylinder means having formed therein an inlet passage adjacent and common to each pair of cylinders and terminating in alignment with the ends of the cylinders, a separate cylinder head for each pair of cylinders, each cylinder head having an inlet chamber communicating with both cylinders and said common inlet passage and an outlet chamber communicating with both cylinders and having a partition between the inlet and outlet chambers extending across each cylinder; valve means clamped between each cylinder head and the associated cylinders and including an inlet valve controlling communication between the inlet chamber and each cylinder and an outlet valve controlling communication between the outlet chamber and each cylinder; means clamped between each cylinder head and the cylinder means providing communication between the inlet chamber and the common inlet passage; and means providing communication between the several inlet passages and a common inlet therefor.
